UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

INTERNAL-COMBUSTION ENGINE.

Application filed March 5, 1925. Serial No. 13,026.

This application is a continuation in part of my application Serial No. 570,349, filed June 23, 1922.

The present invention relates to internal combustion engines, particularly two-cycle engines, and has for its object to provide an improved means for scavenging such engines. It is applicable to either single cylinder or multi-cylinder engines.

For a consideration of what I believe to be novel and my invention, attention is directed to the accompanying description and the claims appended thereto.

In the drawing, Fig. 1 is a diagrammatic view, partly in section, of an internal combustion engine provided with a scavenging means embodying my invention; Fig. 2 is a diagrammatic plan view of the engine shown in Fig. 1; and Fig. 3 is a diagrammatic view similar to Fig. 1 of a modification.

Referring to the drawing, Figs. 1 and 2, 5 indicates a cylinder of a two-cycle internal combustion engine here shown as being an engine of the high compression type. The cylinder is shown as being provided in the present instance with a main scavenging port 6, an auxiliary scavenging port 6^a, an exhaust port 7, and a fuel injector 8. In 10 the cylinder is a piston 9 to which is connected a piston rod 10, the latter having the usual connection to the crank shaft in the well understood manner. A valve 11 is shown for controlling the admission of 15 scavenging air from the scavenging air chamber 12 to the auxiliary port 6^a. It may be suitably operated from the crank shaft to open at the correct time for admitting scavenging air, it being understood that 20 valve 11 will be closed during the down stroke and opened during a portion of the up stroke of the piston. The scavenging port 6 is controlled by the piston 9.

The foregoing engine structure may be 25 taken as typical of any suitable two-cycle single or multi-cylinder engine scavenged by compressed air. It is shown only by way of example and it is to be understood that my invention may be applied to this 30 specific type of engine or to any other type to which it may be found adapted.

Now, according to my invention I provide a centrifugal air compressor for supplying scavenging air to the engine and I

drive such compressor by means of a turbine wheel operated by gases taken from a cylinder or cylinders of the engine. For driving the turbine wheel I utilize preferably gases discharged from a special port or ports located in advance of the regular exhaust port or ports, although as to certain aspects my invention is not limited to this arrangement. In Fig. 1, 14 indicates a centrifugal air compressor of any suitable type provided with an inlet 15 and a discharge conduit 16. Discharge conduit 16 is connected by a pipe 17 to scavenging air chamber 12. The impeller of the compressor is mounted on a shaft 18 carried on a bearing 19. On an end of shaft 18 is 55 mounted a turbine wheel 20 provided with a ring of buckets 21 of any suitable structure. In one or each of the cylinders 5 in advance of port 7 is a special port 22 which communicates with a nozzle box or manifold 60 23 suitably fixed to cylinder 5. Nozzle box 23 is provided with one or more nozzles 24 arranged to discharge exhaust gases against bucket ring 21 to effect rotation of turbine wheel 20 in the well understood manner. Port 22 communicates with nozzle box 23 65 through a passage 25 which may be provided with suitable weighted check valve means 26 which opens outwardly. This valve may be operated in any suitable manner. In the present instance it is shown as being biased towards closed position by its weight and opened by the gas pressure. When the engine is in operation the piston 70 on its out stroke uncovers port 22 prior to the time the scavenging and exhaust ports are uncovered and while there is still considerable pressure left in the cylinder so that a certain amount of gases escape 75 through port 22 to nozzle box 23 and are directed by nozzle means 24 against the buckets of the turbine wheel. A certain pressure will be built up in the nozzle box and this pressure will be sufficient to maintain the turbine wheel at a high speed so 80 that the compressor 14 will deliver a suitable quantity of air at the desired pressure for scavenging the cylinder or cylinders. Preferably all the engine cylinders will be 85 provided with special ports 22 since by this arrangement a more even pressure will be maintained in the nozzle box or manifold 90 23. However, the specific arrangement used 95 100 105

will depend upon the particular conditions met with and the total number of engine cylinders in the engine. The compressor will maintain the desired scavenging air pressure in chamber 12 so that when piston 9 uncovers ports 6 and 7 the scavenging air will rush through the cylinder to force out the spent gases and fill the cylinder with air. If the engine is of a type utilizing auxiliary valve controlled scavenging ports, the arrangement will be such that valve 11 will be opened during the return stroke of the piston to admit a final charge of scavenging air. The valve 26 serves to close port 22 to prevent the flow of gases from the nozzle box back into the cylinder or from the cylinder to the nozzle box during the compression stroke. It will also prevent gases passing into a cylinder when another cylinder is supplying gas at a higher pressure. It will be understood, of course, that in place of a check valve I may use any other type of valve found desirable.

In Fig. 3 I have shown a modification wherein in addition to the port 22 I provide a special exhaust port 30 which is slightly in advance of the regular exhaust port 7 and through which the major portion of the exhaust gases pass. Exhaust port 30 communicates with a chamber 31 from which leads two conduits 32 and 33. Conduit 32 conveys exhaust gases to a port 34 communicating with the atmosphere and conduit 33 conveys exhaust gases to a set of nozzles 35 which direct the gases against the buckets of turbine wheel 20. Conduits 32 and 33 are controlled by two interconnected valves 36 and 37, the arrangement being such that when one valve is closed the other is open. The arrangement is such that during the firing stroke valve 36 is closed and valve 37 is open so exhaust gases may pass to the nozzles 35, while during the compression stroke valve 36 is open and valve 37 is closed so that port 30 is connected to atmosphere. Valves 36 and 37 may be operated by any suitable means so as to be opened and closed at the correct times. In the present instance they are shown as being operated by the pressure of the exhaust gases. To this end the two valves 36 and 37 are connected together by a curved rod 38 and the valve structure thus formed is pivoted at 39, the arrangement being such that the weight of the valve structure biases it to a position wherein valve 37 is closed and valve 36 is open. On the down or firing stroke of the piston, the exhaust gases discharging through port 30, strike valve 37 and force it open, this action taking place because the exposed area of valve 37 is greater than that of valve 36. Valve 37 will be held open and valve 36 will be held closed until the exhaust gas pressure decreases to a value in the neighborhood of atmospheric pressure whereupon

valve 37 will fall by gravity to closed position at the same time opening valve 36. Port 30 is then connected to atmosphere by way of port 34. The exhaust port 7 is connected to atmosphere through a passage 40 and port 41. With this arrangement I utilize the major portion of the exhaust gases for driving the turbo-compressor.

In connection with the construction illustrated in Fig. 3, I have shown a modification wherein the turbine wheel 20 drives compressor means which delivers scavenging air at two different pressures, such compressor means comprising in the present instance two centrifugal compressors 42 and 43. The discharge side of compressor 42 is connected by a conduit 44 to a chamber 45 from which scavenging air is supplied through valve 11 to scavenging port 6^a while the discharge side of compressor 43 is connected by a conduit 46 to the scavenging port means 6. Compressor 42 is preferably designed so that it furnishes air at a pressure somewhat higher than that furnished by compressor 43 so that the final charge of scavenging air supplied to the cylinder through port 6^a serves to provide initially in the cylinder a higher pressure and hence a greater quantity by weight of air. This serves to supercharge the cylinder. It will be understood, of course, that as pointed out above in connection with Fig. 1, valve 26 serves to prevent scavenging air supplied through port 6^a from flowing out through port means 25 and also prevents gases flowing from nozzle box 23 back to the cylinder. Valve 26 is biased toward closed position by its weight and this, plus the pressure in nozzle box 23 is sufficient always to hold valve 26 closed against the scavenging air pressure which, of course, is much lower than the explosion pressure present in the cylinder when port means 22 is uncovered on the firing stroke.

A turbo-compressor set is inherently a high speed apparatus, operating at a speed of the order of 10,000 revolutions per minute, for example. It will therefore be much lighter than any type of separate compressor set such as a reciprocating compressor and will have a lower first cost. Furthermore, as is well known, centrifugal compressor and turbine apparatus requires much less maintenance than reciprocating compressor apparatus.

Apparatus embodying my invention has the further advantage that it is inherently self-governing and will automatically supply the correct amount of scavenging air. With increase in load more scavenging air is required but at the same time there will be more products of combustion at a higher pressure.

Hence the gas turbine will be operated at higher speed and so increase the pressure and amount of scavenging air. With de-

crease in load, the products of combustion will be decreased and this will automatically give a decrease in the speed in the gas turbine and hence a decrease in the amount and 5 pressure of the scavenging air.

In accordance with the provisions of the patent statutes, I have described the principle of operation of my invention, together with the apparatus which I now consider to 10 represent the best embodiment thereof, but I desire to have it understood that the apparatus shown is only illustrative and that the invention may be carried out by other means.

15 What I claim as new and desire to secure by Letters Patent of the United States, is:—

1. The combination with a two-cycle internal combustion engine comprising a cylinder having scavenging and exhaust ports 20 and a piston, of a centrifugal air compressor having its discharge side connected to the scavenging port, a turbine wheel for driving the compressor, walls forming a gas chamber and providing means for directing actuating 25 gases to the turbine wheel, and a port in the cylinder which is opened immediately in advance of the opening of the exhaust port for supplying gases to said chamber, said port being controlled by the piston.

30 2. The combination with a two-cycle internal combustion engine comprising a cylinder having scavenging and exhaust ports and a piston, of a centrifugal air compressor having its discharge side connected to the 35 scavenging port, a turbine wheel for driving the compressor, a nozzle box having nozzle means for directing actuating gases to the turbine wheel, a port in the cylinder which is opened immediately in advance of the opening of the exhaust port for supplying gases to the nozzle box, said port being controlled by the piston, and a non-return valve means for preventing flow of gases from the nozzle box toward the cylinder.

40 3. The combination with a two-cycle internal combustion engine comprising a cylinder having scavenging and exhaust ports and a piston, of a centrifugal air compressor having its discharge side connected to the 45 scavenging port, a turbine wheel for driving the compressor, a nozzle box having nozzle means for directing actuating gases to the turbine wheel, a port in the cylinder which is opened immediately in advance of the opening of the exhaust port for supplying gases to the nozzle box, said port being controlled by the piston and a non-return valve means controlled by the pressure of the gases in the nozzle box for covering and 55 uncovering said last-named port to prevent flow of gases from the nozzle box toward the cylinder.

60 4. The combination with a two-cycle internal combustion engine, comprising a cylinder having scavenging and exhaust ports

and a piston, of a centrifugal air compressor having its discharge side connected to the scavenging port, a turbine wheel for driving the compressor, nozzle boxes having nozzle means for directing actuating gases to the 70 turbine wheel, and a plurality of ports in the cylinder which are opened immediately in advance of the opening of the exhaust port for supplying gases to the nozzle boxes, said ports being controlled by the piston. 75

5. The combination with a two-cycle internal combustion engine comprising a cylinder having scavenging and exhaust ports and a piston, of a centrifugal air compressor having its discharge side connected to the 80 scavenging port, a turbine wheel for driving the compressor, nozzle boxes having nozzle means for directing actuating gases to the turbine wheel, a plurality of ports in the cylinder which are opened immediately in 85 advance of the opening of the exhaust port for supplying gases to the nozzle boxes, said ports being controlled by the piston and non-return valve means for preventing flow of gases from the nozzle box toward the cylinder. 90

6. The combination with a two-cycle internal combustion engine comprising a cylinder having scavenging and exhaust ports and a piston, of a centrifugal air compressor 95 having its discharge side connected to the scavenging port, a turbine wheel for driving the compressor, and a plurality of exhaust ports in the cylinder arranged one in advance of another for supplying gases to 100 actuate the turbine wheel, said ports being controlled by the piston and being opened immediately in advance of the opening of the exhaust port.

7. The combination with a two-cycle internal combustion engine comprising a cylinder having scavenging and exhaust ports and a piston, of a centrifugal air compressor having its discharge side connected to the 105 scavenging port, a turbine wheel for driving the compressor, a plurality of exhaust ports in the cylinder, said ports being controlled by the piston and being opened immediately in advance of the opening of the exhaust port, a nozzle box to which one of said 110 exhaust ports is connected, a second nozzle box, and valve means for connecting another of said exhaust ports to either the second nozzle box or to atmosphere. 115

8. The combination with a two-cycle internal combustion engine comprising a cylinder structure having two sets of scavenging ports one of which is opened in advance of the other, and exhaust port means, of 120 centrifugal air compressor means provided with two discharge conduits for receiving air of different pressures from the compressor means, means connecting the discharge conduits to said two sets of scavenging ports, 125 a turbine wheel for driving the compressor 130

means, and means for supplying gases from the cylinder structure to drive the turbine wheel.

9. The combination with a two-cycle internal combustion engine comprising a piston and a cylinder structure having two sets of scavenging ports one of which is opened in advance of the other, and exhaust port means, of centrifugal air compressor means 5 provided with two discharge conduits for receiving air of different pressures from the compressor means, means connecting the discharge conduits to said two sets of scavenging ports, a turbine wheel for driving the 10 compressor means, and port means in the cylinder structure which is opened in advance of opening the said exhaust port means for supplying gases to drive the turbine wheel, said port means being controlled 15 by the piston.

10. The combination with a two-cycle internal combustion engine comprising a cyl-

inder structure having two sets of scavenging ports one of which is opened in advance of the other, and exhaust port means, of air 25 compressor means provided with two discharge conduits for receiving air of different pressures from the compressor means, means connecting the discharge conduits to said two sets of scavenging ports, and means for 30 driving said compressor means.

11. The combination with a two-cycle internal combustion engine having two sets of scavenging ports, one in advance of the other, of centrifugal compressor means for 35 supplying air to each of said sets of ports, the air supplied to one of said sets being of a pressure higher than that supplied to the other, and means actuated by gases from the engine for operating said compressor 40 means.

In witness whereof, I have hereunto set my hand this 3rd day of March, 1925.

SANFORD A. MOSS.
